C. SMALL

HOT WATER BOTTLE

Filed Nov. 21, 1923

UNITED STATES PATENT OFFICE.

CLARENCE SMALL, OF BINGHAMTON, NEW YORK.

HOT-WATER BOTTLE.

Application filed November 21, 1923. Serial No. 676,092.

To all whom it may concern:

Be it known that I, CLARENCE SMALL, citizen of the United States, residing at Binghamton, in the county of Broome and 5 State of New York, have invented certain new and useful Improvements in Hot-Water Bottles, of which the following is a specification.

This invention relates to an improvement 10 in hot water bottles, and has more particular reference to a bottle wherein the same is composed of a non-collapsible puncture proof material, preferably aluminum, hardened rubber, or fiber, whereby there will be 15 little liability of the same becoming disrupted and the contents discharged upon the patient, which is now a prevalent disadvantage in hot water bottles universally used.

One of the primary objects of my invention 20 resides in the provision of such a hot-water bottle wherein the same is so shaped as to permit the same to lie flush with the different parts of the body of the patient for thereby dispensing with any discomfort 25 that would otherwise be present.

A still further object is to provide an 30 article of the above character that may be employed also as a syringe, and this by merely replacing the stopper used when the article is employed in the hot water bottle by a somewhat similar stopper that is provided with an outlet to which is attached one 35 end of the usual rubber tubing for allowing the contents thereof to discharge through the tubing when the bottle is inverted.

With the above and other objects in view, as the nature of the invention will be better understood, the same comprises the novel 40 form of hot water bottle hereinafter more fully described, shown in the accompanying drawings and claimed.

In the drawings, wherein like reference characters designate corresponding parts throughout the several views:

45 Figure 1 is a side elevational view of a hot water bottle constructed in accordance with my invention.

Figure 2 is a rear elevational view thereof.

Figures 3 and 4 are detailed vertical and 50 transverse sectional views taken substantially upon the lines 3-3 and 4-4 respectively of Figure 2, and

55 Figure 5 is an elevational view of the stopper member per se that is to be employed when the device is to be used as a syringe.

Now, having particular reference to the drawings, wherein there is disclosed a combination hot water bottle and syringe constructed in accordance with this invention, the same comprises a body portion 5 and a neck portion 6 the upper end of which flares outwardly for providing a filling funnel 7. The body and neck portions forming said bottle are integrally joined together and are composed of a non-frangible and non-collapsible material, preferably aluminum, hard rubber, or fiber, molded into the shape shown.

The body portion 5 of the bottle is preferably of rectangular shape, the rear wall 8 of which is concaved in a direction of its length, the front wall 9 thereof being convex in the direction of its width for consequently allowing the bottle to be placed upon the parts of the body affected, and this without causing any discomfort to the patient, it being of course understood that by manufacturing a bottle of this nature from metal, hard rubber, or fiber, there will be little or no liability of the same becoming punctured and consequently allowing the contents thereof to discharge upon the patient.

Within the neck portion 6 of the bottle, there is formed, as shown in Figure 3, screw threads 10 for receiving the usual screw threaded stopper 11, or the type of stopper 12 shown in Figure 5, as desirable, said last mentioned stopper being of conventional form, that is provided with a central passage in communication with which is the one end 85 of a flexible tubing 13, to the other end of which may be attached any form of syringe fitting for allowing the device to be employed as a syringe.

The end of this bottle opposite from the neck portion is formed with a lug or ear 14 that is provided with an opening 15, whereby the device may be inverted and supported upon a hook or other element for allowing the contents to discharge thru the stopper 12 100 and into the tubing 13 when the article is employed as a syringe.

Numerous advantages of an article of this character will be at once appreciated by those having occasion to use the same, and even though I have herein set forth the most practical embodiments of the invention with which I am at this time familiar, it is nevertheless to be understood that minor changes 105 may be made therein without departing 110

from the spirit and scope of the appended claim.

Having thus described my invention what I claim as new and desire to secure by Letters

5 Patent is:

A hot water bottle comprising a body formed of rigid material having opposite

side walls, one of the side walls being concaved transversely of the body and the opposite side wall being convexed longitudinally of the body. 10

In testimony whereof I affix my signature.

CLARENCE SMALL.
